FRAME STRUCTURE FOR MULTICRANK-
SHAFT ENGINESGustav Pielstick, Saint-Germain-en-Laye,
FranceApplication July 2, 1949, Serial No. 102,810
In France July 9, 1948

1 Claim. (Cl. 60—97)

1
This invention relates to multi-crankshaft engines of the general type described and claimed in my copending U. S. patent application Ser. No. 102,808 filed concurrently herewith for: "Improvements in and Relating to Multicrankshaft Engines" and is more specifically concerned with the provision of an improved frame structure for such an engine.

In my said co-pending application Ser. No. 102,808 I describe an improved arrangement of the component parts of a combustion engine whereby it is possible to construct high-powered unitary power-plants having reduced dimensions and wherein the power output at any time may be simply and efficiently fractionized according to the particular power requirements at that time, thereby to achieve substantial savings in fuel even under reduced load operating conditions. The said arrangement consists of the provision of a plurality of laterally-spaced crankshafts, arranged generally parallel or slightly at an angle with one another, and a plurality of banks of cylinder-and-piston drive units extending parallel and adjacent to related ones of said crankshafts, the units in each bank being each adapted to actuate corresponding crank-throws of the crankshafts related to that bank. The crankshafts are described as having their crank-throws in equal numbers with the corresponding throws of all of the crankshafts located in common transverse planes. And the cylinders in the respective banks are stated as being vertical or inclined. Moreover, some preferred specific embodiments are shown and described as comprising three and four crankshafts.

In my further concurrently-filed co-pending U. S. patent application, Ser. No. 102,809 for "Improvements in and Relating to a Frame Structure for Multicrankshaft Engines," I describe and claim a frame structure particularly designed for a power-plant arrangement of the above mentioned general type. The engine frame described and shown therein essentially comprises a unitary integral element or elements integrally and rigidly assembled together and formed adjacent its base with means for rotatably mounting at least a lower pair of crankshafts with their related banks of cylinders and at its top with means for similarly mounting the remaining crankshaft (or crankshafts) of the multicrankshaft power plant with its (or their) related banks of cylinders. The whole arrangement of the engine frame is described as symmetrical with respect to a vertical longitudinal centre plane. Partitioning means are provided

2
to define individual operating chambers for the crankshafts with oil sumps at the bottom of the chambers.

A fundamental characteristic of such second application is the fact that the lower pair of units and their bellied crankshaft areas together with the oil sumps therefor, are wholly located within the lower contour area of the frame, while the similar formations of the upper units are located above the upper contour area of the frame, the wall of the latter contour forming the lower wall of the sump or sumps of the upper units of the assembly. The piston and cylinder elements of all of the units extend upwardly from the bellied crankshaft areas, with the elements of the upper unit or units being positioned between the similar elements of the lower pair of units. This arrangement inherently locates the symmetrical axis of the assembly, the axis of which is symmetrical to the individual axes of all of the bellied areas of the assembly, and forming the axis of the drive shaft of the assembly, above and spaced from the mid or axial area of the frame, with the latter spaced above and angularly related to the axes of the bellied areas of the pair of lower units, with the angle between the mid or axial area and each lower bellied area axis being at least equal to 90°. Since this specific arrangement represents the unit formation transversely of the assembly and the assembly includes a longitudinal succession of such transverse formations individually cooperative with different cranks or throws of the respective crankshafts, presenting the usual bank characteristic of internal combustion engine assemblies of the complete unit assembly or power unit is provided by such assemblage of structural features.

In the construction of high-powered power-plants, particularly in ships where it is required to obtain a high power-output on a screw-shaft, the necessity may frequently arise of providing two or more unitary power-plants or power-units of the type described arranged in longitudinal alignment with one another. It then becomes necessary to lead the output shaft from one unit assembly through the engine-frame of another unit assembly located between the first unit assembly and the screw. In Figure 3 of my copending application Ser. No. 102,809 there is shown an engine frame designed for such purpose and comprising a central recess or tunnel adapted to provide separating and supporting means for such a shaft extending from another unit assembly. It is a general object of this invention to amplify on the teachings of said ap-

lication Ser. No. 102,809 as regards the construction of such a special engine frame.

An object of the present invention is to provide a multicrankshaft engine frame of the type described which comprises means for leading an output shaft extending from another power unit through said engine frame in such a way that said shaft will be supported therein while not interfering with the operation of the crankshafts—operatively mounted in said frame.

Another object is to provide a multicrankshaft engine frame of standard construction which will enable the arrangement of two or more multicrankshaft power plants in longitudinally-aligned relationship with one another and each of which may comprise a similar type of standard frame, whereby said two or more power plants may be made to drive a common output shaft.

A further object is to provide such a standard multicrankshaft engine frame construction formed with a longitudinal through recess therein such that when said recess is not used to lead a central output shaft therethrough, it may be sealed so as to form a container as for a supply of fresh lubricant or other purposes.

Other and further objects and advantages of the invention will appear from a perusal of the ensuing disclosure when read in conjunction with the accompanying diagrammatical drawing, given for purposes of illustration merely and not of limitation, and wherein:

Figure 1 is a cross-sectional view of a multicrankshaft engine frame according to the present invention.

Figure 2 is a side elevation of the frame portion of one of the unit assemblies or power units, the view including a sectional portion of one of the transverse unit structures of the Figure 3 form, the section being taken on line II—II of Fig. 3, the view also indicating the bank characteristic as to the length of the power unit.

Figure 3 is a cross-section on line III—III of Fig. 2 of the same embodiment.

As shown in Fig. 1, the engine frame is generally indicated at 1. Mounted in the lower portion of the frame 1 and wholly within the contour of the frame are a lower pair of crankshafts 2, 3 and the related substantially upstanding banks of cylinders 4 and 5. The arrangement is symmetrical on each side of the vertical centre plane X—X of the frame. A bottom cover 6 seals the base of the frame and defines a pair of oil sumps or chambers 7.

The frame 1 adjacent its top mounts a pair of upper crankshafts 8, 9 and their sumps 12 and 13 with the upstanding cylinder banks 10, 11 related thereto.

In the latter structure, the upper contour of the frame forms the lower wall of the upper units and the sumps 12 and 13. As a result of such arrangement, it is apparent that the symmetrical axis of the assembly, the axis symmetrical to the bellied areas of the crankshafts of all of the units, is located above the mid or axial area vertically of the frame. In addition, the axes of the lower pair of bellied crankshaft areas are each located a material distance below such mid or axial area of the frame and angularly related thereto at an angle of at least 90°.

Between the upper oil sumps or chambers 12, 13 a recess or tunnel 14 is defined adapted to have extending therethrough a drive or output shaft 15 leading from a rearwardly-arranged power plant 16, as shown in Fig. 2. The walls of the tunnel 14 are defined by the walls a and b of the

upper oil sumps 12 and 13, and the walls c and d of the lower oil sumps or chambers 7. The sides of the tunnel 14 are completed by inclined sheet elements 16 and 17 as shown thus providing a sealed enclosure for the tunnel 14.

The embodiment illustrated in Figs. 2 and 3 differs from that just described in connection with Fig. 1 merely in that the upper banks of cylinders 10 and 11 are inclined rather than vertical. As a result the pattern in cross-section is somewhat altered. The essential features nevertheless remain the same as in the first-described embodiment, as may readily be ascertained from a comparison of Figures 1 and 3, in which similar references have been used to designate corresponding parts. Figure 2 presents a side elevation of the frame portion of a unit assembly made up of all the assembly units which are contained in the bank which represents the length of the assembly, the frame being based on the structure shown in Figure 3. A portion of the view (Fig. 2) is a section of one of the transverse unit structures of Figure 3 with the section taken on line II—II of said figure, the length of the frame indicating a succession of such transverse structures with each cooperating with a different crank or throw of the crankshafts. As indicated, the opposite ends of the frame are provided with end bearings 18 and 19, these being arranged relative to the symmetrical axis and forming the support for the section of the drive shaft which is individual to the unit assembly or power unit.

Since the present invention is designed for service under heavy duty conditions, the invention contemplates the use of a plurality of such unit assemblies or power units, these being arranged in succession longitudinally. Inasmuch as such service may vary, as with ship propulsion, the drive shaft 15 is made individual to the power unit, with the ends of the sections arranged to be coupled together to form a continuous shaft. This permits variations in the power employed in service, since it would be possible to uncouple power units by disengaging the connections between shaft sections, or to increase the power by increasing the number of power units active in service by coupling the drive shaft sections together.

As will be understood, a multi-power assemblage of such type may be very lengthy, as in ship propulsion service, by the use of a plurality of such power units, yet the width or transverse dimensions of the assemblage are comparatively narrow and are substantially uniform from end to end.

In a power plant assembly including a plurality of multi-crankshaft power units of the type contemplated herein, all the units of said plurality may be provided with engine frames of the general structure described in the application. Where in any of said units the central tunnel 14 is not used as a passage for an output shaft, it may be sealed at the ends thereof with any suitable cover plates, not shown, and may then be used as a container, for example to hold a supply of fresh lubricant oil or the like purposes, thereby eliminating an additional tank of comparatively large capacity, which might otherwise be required.

It will of course be understood that the invention is not restricted to the specific details of construction illustrated and described, but only by the scope defined in the ensuing claim.

What I claim is:

In a power plant of the multi-crankshaft type, comprising a plurality of power units, each com-

prising aligned cylinders and pistons with a related crankshaft, gear means connecting said crankshaft to a main power shaft, a central structural frame supporting all of said units, two of said units having their respective crankshafts located in the lowermost part of said frame and below the central axis thereof, said two power units having their cylinders projecting upwardly from said frame, the lines connecting said central axis with the axis of each crankshaft of said lower power units forming an angle of at least 90°, the plane passing through the projecting cylinders and the crankshafts of said lower power units forming an acute angle with the vertical, the remaining one or two power units being mounted on the upper part of the frame symmetrically with respect to said frame central axis, and an open ended tunnel shaped passageway in the

central portion of said frame formed by partitions provided within said frame, said tunnel forming a passageway for the main powershaft of the power plant or for a main powershaft of another independent powerplant in alignment with the first powerplant.

GUSTAV PIELSTICK.
